UNITED STATES PATENT OFFICE.

AUGUST WM. SCHEUBER, OF NEW YORK, N. Y., ASSIGNOR TO SIMON ZINN,
OF SAME PLACE.

DESIGN FOR A FRAME FOR POCKET-BOOKS.

SPECIFICATION forming part of Design No. 25,278, dated March 24, 1896.

Application filed January 30, 1896. Serial No. 577,468. Term of patent 7 years.

To all whom it may concern:

Be it known that I, AUGUST WM. SCHEUBER, a citizen of the United States, residing at New York, in the county and State of New York, have invented and produced a new and original Design for a Frame for Pocket-Books, Bags, and other Articles, of which the following is a specification.

This design has for its object to provide a novel, handsome, and ornamental frame for a pocket-book, purse, bag, or similar article; and the leading feature of the design consists in a frame composed of a rectilinear main body portion or section, portions or sections extending, respectively, from the ends of the main body portion or section at obtuse angles thereto, and rectilinear portions or sections extending from the ends of the obtuse-angled portions or sections and arranged at right angles to the rectilinear main body portion or section.

The design is illustrated by the accompanying drawings, in which—

Figure 1 is a top plan view of a pocket-book

frame made according to my design, and Fig. 2 is a side elevation of the same.

In the drawings the numeral 3 indicates the rectilinear main body portion or section, and 2 the portions or sections which extend from the ends of the main body portion or section at obtuse angles thereto. The rectilinear portions 1 extend from the ends of the obtuse-angled portions or sections 2 and are located at right angles to the rectilinear main body portion or section 3.

The design provides a novel and handsome frame, which presents a characteristic and distinguishing appearance to the eye.

What I claim is—

The design for a pocket-book frame, substantially as shown and described.

In testimony whereof I have hereunto set my hand in the presence of two subscribing witnesses.

AUGUST WM. SCHEUBER.
